US00D590354S

(12) **United States Design Patent**
Tsuchiya et al.

(10) **Patent No.:** **US D590,354 S**
(45) **Date of Patent:** **** Apr. 14, 2009**

(54) **LIGHT-EMITTING DIODE**

(75) Inventors: **Kosuke Tsuchiya**, Fujiyoshida (JP);
Kazuya Ishihara, Tsuru (JP)

(73) Assignee: **Citizen Electronics Co., Ltd.**,
Yamanashi (JP)

(**) Term: **14 Years**

(21) Appl. No.: **29/318,851**

(22) Filed: **May 29, 2008**

(30) **Foreign Application Priority Data**

Nov. 29, 2007 (JP) 2007-032796

(51) **LOC (9) Cl.** **13-03**

(52) **U.S. Cl.** **D13/180**

(57) **CLAIM**

The ornamental design for a light-emitting diode, as shown and described herein.

DESCRIPTION

FIG. 1 is a perspective view of light-emitting diode in accordance with the present design, as viewed from front;

FIG. 2 is a perspective view thereof as viewed from below;

FIG. 3 is a front plan view thereof;

FIG. 4 is a rear plan view thereof;

FIG. 5 is a top plan view thereof;

FIG. 6 is a bottom plan view thereof;

FIG. 7 is a left side view thereof;

FIG. 8 is a right side view thereof; and,

FIG. 9 is a sectional view taken along the 9—9 line in FIG. 3 showing the present design.

The article is used as a light source for key illumination in vehicles, for a backlight unit to illuminate a liquid crystal display and the like.
